COLLAR CLASP

William H. Schoonmaker, Montclair, N. J.

Application December 12, 1931. Serial No. 580,567

3 Claims. (Cl. 24—81)

This invention relates to collar clasps and more particularly to clasps of the type commonly used for engagement with soft collars and positioned under a necktie.

5 Heretofore, several types of tie clasps or pins have been used. In one type of device, pins formed as a part thereof completely pierce each tab of the collar, leaving disfiguring holes therein and, furthermore, eventually causing wear-
 10 ing out of the collar in the localities in which the penetration is accomplished. In another type of device substantially smooth spring members are utilized for holding the tabs of the collar between the spring members and the bar of the de-
 15 vice. These spring members must be flexed when engagement is made with the collar tab, with the result that the collar becomes wrinkled. Moreover, with devices of this character there is no provision made for preventing slipping of
 20 the device relative to the collar, which slipping will take place to some extent, regardless of the tension of the spring members.

An object of the invention is to provide a simple collar clasp, inexpensive to manufacture, and
 25 efficient in operation.

Another object of the invention is to provide a collar clasp which is readily engageable with and disengageable from a collar.

A further object of the invention is to pro-
 30 vide a collar clasp which, when engaged with a collar, is held substantially immovable relative thereto without causing mutilation of the part of the collar in engagement therewith.

According to the present invention the faults set forth hereinbefore are overcome in the following manner: The device consists simply of a bar, preferably flat, which bar may be curved or not as occasion may demand. Secured to one side of the bar are a pair of tabs, each of which carry short gripping members which will engage the material of the collar. These tabs are naturally secured to the bar near the respective ends thereof. In one form of the invention the gripping member carrying tabs are formed as an integral part of a leaf spring which is secured to the bar by means of pivotal connec-
 40 tions spaced a short distance from each end of the bar. These pivotal connections are of such character that the length of leaf spring there-
 45 between is greater than the length of bar there-
 50 between, with the result that the spring either presses the tabs toward the bar or else holds the same away therefrom.

In another form of the invention the tabs
 55 are entirely separate, being pivotally mounted

near each end of the bar and being provided with parts extending toward the center of the bar. Coiled springs are wound around the pin used in the pivotal connection in such manner as to normally force the tabs toward the bar. By 60 pressing on the extensions of each tab, gripping member carrying parts thereof may be forced away from the bar, permitting engagement of the clasp with the collar.

Other features, objects and advantages of the 65 present invention will become readily apparent by reference to the following detail description taken in connection with the accompanying drawing forming a part of the same, wherein

Figure 1 is a perspective view of one form of 70 the invention with the gripping member carrying tabs forced away from the bar to permit engagement with the collar;

Figure 2 is a similar view of the same device, with the gripping member carrying tabs forced 75 toward the bar;

Figure 3 is an enlarged side elevation of the device shown in Figure 1, the arrangement being illustrated in reversed position;

Figure 4 is a view similar to Figure 3 of the 80 device, as illustrated in Figure 2;

Figure 5 is a plan view of the device as shown in Figure 4;

Figure 6 is a side elevation of a modification 85 of the invention, and

Figure 7 is an enlarged section taken substan-
 90 tially on the lines 7—7 of Figure 6.

Referring now to the drawing and particularly to Figures 1 to 5, inclusive, 10 indicates a bar forming a part of a collar clasp, the bar in this instance being substantially flat. It is not essential, however, that the bar be flat since, as conditions may warrant, the same may be slightly curved or given any other desired configuration. Extending from one side of the bar 10 and spaced 95 from the ends thereof are pairs of bearing members 11. A leaf spring 12 has bearing members 13, through which passes a pin 14, the pins 14 also passing through the bearing members 11, thereby forming pivotal connections between the 100 leaf spring 12 and the bar 10.

Portions 15 at each end of the leaf spring 12 form tabs which are provided with short gripping members 16, extending toward the bar 10.

In order that the tabs 15 may be forced toward 105 the bar 10 or away therefrom, the expanse of leaf spring 12 between the pivotal connections thereof is greater than the expanse of bar 10 between the same points. As a result of this arrangement the leaf 12 may be flexed so that its central 110

portion presses against the bar 10, thereby moving the tabs 15 away from the same bar, or so that the middle part is bowed outwardly from the bar 10 with the tabs forced toward the same. 5 The respective positions of the leaf 12 are shown in detail in Figures 3 and 4.

The operation and use of the tabs, as illustrated in Figures 1 to 5, inclusive, is substantially as follows: When it is desired to engage the device 10 with the respective ends of a collar, the tabs 15 are forced away from the bar 10 into the position shown in Figure 3. The device is then ready to be positioned relative to the collar. As soon as the clasp has been properly positioned relative 15 to the collar, it may be locked thereto by merely pressing one or both ends of the leaf 12. A slight bit of pressure applied to one or both of the tabs 15 will serve to cause the middle part of the leaf to be flexed into the position shown in Figure 20 4. In this position, the members 16 will grip the material of the collar sufficiently to hold the clasp substantially immovable relative to the collar. The pins, however, do not completely penetrate the material of the collar so that 25 when the clasp is disengaged therefrom by merely applying pressure to the middle part of leaf 12, no unsightly holes are left in the collar. Moreover, the penetration of the pins into the collar is not of such character as would cause 30 wear of the collar to any appreciable extent.

In the embodiment of the invention shown in Figures 6 and 7, use is made of a bar 20 of appearance similar to bar 10. The bar 20, however, may be a composite bar made up of a solid 35 portion 21, together with an inlay 22. The solid part has extending therefrom near each end bearing standards 23. Tabs 24 provided with bearing standards 25 are pivotally mounted to the bar by means of pins 26 extending through the standards 23 and 25. The tabs 24 are provided 40 with gripping members 27 similar to members 16 before described. These tabs 24 have prolongations 28 extending toward the center of the bar and formed integrally with the tabs themselves. Springs 29 are coiled around each pin 45 26 with the ends 30 of the spring pressing respectively against the prolongations 28 and the bar 20.

The operation and use of the modification shown in Figures 6 and 7 is substantially as follows: When it is desired to engage the clasp with a collar the two prolongations 28 are pressed 50 toward the bar 20 (as shown in dotted lines in Figure 6), in which position the points or tabs of the collar may be inserted between the bar 20 and the two tabs 24. When the collar is properly positioned, the prolongations 28 are released, at

which time the two springs 29 force the prolongations outwardly, thereby pressing the tabs 24 into contact with the material of the collar. When such contact is made the members 27 grip the collar in the same manner as the members 16 of the other embodiment of the invention. When it is desired to remove the clasp, it is necessary only to reverse the operation; that is, to press the prolongations 28 toward the bar 20, thereby releasing the gripping members from the collar. 80 85

From the foregoing, it will be seen that the present invention in either embodiment constitutes an improved collar clasp which is readily engageable with and disengageable from a collar; which does not mutilate the collar to any appreciable extent; and which will not slip relative to the collar once it has been engaged therewith. Due to the fact that the portion of the clasp bar in engagement with the outside of the collar is smooth, the collar is not made unsightly, since the smooth bar will slip easily over the collar surface. It will be apparent that the invention is capable of further modification, in view of which it is not to be limited by the illustrated embodiments but only by the scope of the 100 following claims.

I claim:

1. A clasp of the character described comprising a bar, a leaf member pivotally secured to said bar in such manner as to form a spring, the 105 ends of which constitute tabs resiliently forced toward the bar in one position and away therefrom in another position, and gripping members extending from each tab.

2. A clasp of the character described comprising a bar, a leaf member pivotally secured to said bar near the ends thereof, the expanse of leaf member between the points of pivotal connection being greater than the shortest distance between the same points, whereby the ends of 115 the leaf may be resiliently forced toward and away from the bar and gripping members extending from the ends of the leaf.

3. A clasp of the character described comprising a bar, a leaf member pivotally secured to said 120 bar near the ends thereof, the expanse of leaf member between the points of pivotal connection being greater than the shortest distance between the same points, whereby the ends of the leaf may be resiliently forced toward and away 125 from the bar and members extending from the ends of the leaf in position to grip material inserted between the ends of the leaf and the ends of the bar.
